James R. Jones, Lakewood, N. Y., assignor to Art Metal Construction Company, Jamestown, N. Y.

Application February 24, 1939, Serial No. 83,188

Term of patent 7 years

To all whom it may concern:

Be it known that I, James R. Jones, a citizen of the United States, residing at Lakewood, Chautauqua County, State of New York, have invented a new, original, and ornamental Design for a Drawer Pull or Similar Article, of which the following is a specification, reference being had to the accompanying drawing, forming a part thereof.

In said drawing:

Fig. 1 is a plan view of a drawer pull showing my design.

Fig. 2 is a front elevation thereof.

Fig. 3 is a rear elevation.

Fig. 4 is a longitudinal section thereof on line 4—4, Fig. 3.

Fig. 5 is a transverse section thereof on line 5—5, Fig. 3.

I claim:

The ornamental design for a drawer pull or similar article, substantially as shown.

JAMES R. JONES.
